PARASITIC FILTER

George L. Usselman, Port Jefferson, N. Y., assignor to Radio Corporation of America, a corporation of Delaware

Application March 30, 1940, Serial No. 326,932

4 Claims. (Cl. 179—171)

This invention relates to an improved type of anti-parasitic filter which damps out the parasitic oscillations with least effect on the normal operation of an oscillator or amplifier stage of the radio transmitter.

An object of this invention is to provide a simplified and improved filter system for damping out parasitic oscillations of an amplifier or oscillator stage.

The usual practice known in the prior art has been to connect a filter consisting of parallel connected inductances and resistances to the midpoint of a plate tank coil of a vacuum tube stage to prevent a type of parasitic oscillation. In some cases, the normal amount of oscillating current or the fundamental or harmonic frequency is great enough to cause considerable loss of power in the resistor. Quite often, it occurs that this parasitic circuit tends to generate much lower frequency oscillation. Consequently, by my invention, I propose to improve the type of filter known in the prior art by connecting in parallel with the inductance and resistance a by-pass condenser. This type of filter would have a low impedance to the normal operating oscillating currents, but it would have a high impedance to the lower frequency parasitic oscillating currents. This would combine low filter loss for normal operation and an effective filter or choke for the parasitic frequencies.

This invention will best be understood by referring to the accompanying drawing, in which the filter portion is shown as F and consists of a choke inductance L, a resistance R, which is preferably non-inductive, and a fixed or variable condenser C. These three elements are all connected in parallel. The filter F is connected in series with the parasitic circuit and as shown by the drawing is connected to the midpoint tap 1 of the output inductance 2 of a typical push-pull amplifier stage. An equivalent to the midpoint tap 1 may be any connection on any high frequency apparatus or circuit which is of substantially zero radio frequency potential with respect to ground. Inductance 2 has connected in parallel therewith a variable tuning condenser 3. The push-pull amplifier stage includes an exciter circuit 4 connected to an input inductance 5 having a midpoint tap 6, the outer ends of inductance 5 being connected to the grids 7 and 8 of two electron discharge devices 9 and 10. The cathodes 11 and 12 are connected to ground at point 13. Grid bias is obtained from a direct current source 14 and a by-pass condenser 15 is connected between the bias and cathode circuits. A tuning 55

condenser 16 is also connected to the outside ends of inductance coil 5. Grids 7 and 8 are neutralized by variable condenser 17 and 18. The anodes 19 and 20 are connected to the outside ends of output inductance 2. The output of the amplifier is coupled to inductance 2 by means of a coupling coil 21. The midpoint of inductance 2 is connected to one side of filter F, the other side of the filter being connected to the positive side of the "B" supply and a by-pass condenser 22 being connected in series from one side of the filter to ground 13. Push-pull amplifier stages, similar to that shown above, are often subject to what is sometimes called "push-pull parasitic oscillations," in which the center tap connection 1 of the plate circuit is part of the parasitic circuit. One method of preventing this parasitic occurrence is to insert an impedance in the circuit at this point. If the impedance is too large, it will interfere with the normal operation of the amplifier; if it is too small, it will not hinder the parasitic oscillations. The filter that will stop the parasitic oscillation is sometimes a large enough impedance to interfere with the efficiency of the amplifier which depends on a ground path for the second harmonic current.

In the operation of the filter of this invention, the choke L carries substantially all the direct plate or anode current and chokes out substantially all high frequency current. Condenser C carries a large part of the normal operating ultra-high frequencies, such as the fundamental and the harmonics. Most of the parasitic current, usually of lower frequency, is forced to follow the path through the resistor R and is consequently damped out.

I have found that for efficient operation of a filter of this invention, for a frequency of 10,600,000 cycles per sec., for an amplifier, the inductance L should have a value of 150 microhenries, resistance R a value of 110 ohms, and the capacity of condenser C a value of 370 micro-micro-farads.

Although this invention is shown as being applied only to a push-pull amplifier, it is to be distinctly understood that it will also equally apply to an oscillation circuit. Therefore, it should not be limited to the specific embodiment shown by the drawing.

What is claimed is:

1. A filter system for a push-pull amplifier circuit operated at frequencies in the order of 10,600,000 cycles per second, said push-pull amplifier being subject to parasitic oscillations in the normal operation thereof, means to damp

out said parasitic oscillations, said means comprising a connection point on the push-pull amplifier output circuit which is at substantially zero radio frequency potential with respect to ground, an inductance of 150 microhenries, a resistance of 110 ohms, and a condenser of 370 micro-microfarads connected together in parallel and in series with the connection point on said amplifier output circuit and ground.

2. In combination a pair of tubes each having an anode, a cathode and a grid, a tuned circuit connected across the grids, a tuned circuit consisting of inductance and capacity connected across the anodes, and means for preventing parasitics and permitting high efficiency operation at fundamental frequency, consisting of a circuit connected from the midpoint of said inductance across the anodes to ground, said circuit including a resistor, an inductance and a capacity connected in parallel.

3. A push-pull amplifier circuit filter system comprising a pair of electron discharge devices each having an anode, a cathode and a grid, a tuned circuit connected across said grids, a tuned

5 circuit consisting of an inductance and capacity connected across said anodes, a mid-point tap on said inductance, and means for preventing parasitics and permitting high efficient operation at the fundamental frequency, said means including an inductance, a condenser and a resistance connected in parallel with each other and in series with said mid-point tap and ground.

10 4. A push-pull amplifier circuit filter system comprising a pair of electron discharge devices each having an anode, a cathode and a grid, a tuned circuit connected across said grids, a tuned circuit consisting of an inductance and capacity connected across said anodes, a mid-point tap on said inductance, and means for preventing parasitics and permitting high efficient operation at the fundamental frequency, said means including an inductance, a condenser and a resistance connected in parallel with each other and in series with said mid-point tap and one side of a condenser, the other side of said condenser being connected to ground.

GEORGE L. USSELMAN.
